DUPLEX SAFETY WINDOW

Application filed July 17, 1930. Serial No. 468,580.

This invention relates to window frames and sashes, and particularly to double hung windows in which two sashes are individually slidable between upright frame members. 5 Such structures should include weather proofing devices to prevent the entrance of rain and wind, heat or cold, and also provide means for ventilation when required.

It is furthermore desirable that either sash 10 may be readily raised or lowered, freely and smoothly, without binding or appreciable wear of the parts in frictional contact.

It is also regarded as advantageous to arrange the sashes in such manner as to permit 15 them to swing upon pivots into various angularly inclined positions within the room, whereby both sides may be presented for cleaning or similar purposes, avoiding the hazards and inconvenience usually encountered in such operations, the sash being spring-locked in whatever position it is caused to assume, assuring the most complete ventilation.

Another aim is in the production of a device 25 readily applied to any common type of window, without mutilating the frame, whereby the sashes may be pivoted, the device being inexpensive and easily applied.

These advantageous objects are attained 30 by the novel construction and arrangement of few and simple parts hereinafter described and shown in the annexed drawings, forming an essential part of this disclosure, and in which:—

35 Figure 1 is a perspective view showing a conventional type of window frame and sash, illustrating an application of the invention, the sashes being shown in an extreme extended position.

40 Figure 2 is an enlarged transverse sectional view of a portion of a window frame with inner and outer sashes engaged therein, showing the application of the invention.

Figure 3 is a longitudinal sectional view 45 of the same.

Figure 4 is a side elevational view of the device ready to be attached to the edge of a wooden window sash.

Figure 5 is an edge view of the same.

50 Figure 6 is a rear elevational view thereof.

Figure 7 is a side elevational view of the device showing its connecting elements as in a partial open position.

Figure 8 is a perspective view of the device shown in a fully extended position, and 55 looking from the side opposite that seen in Figure 7.

In the drawings the numeral 10 designates the sill of a conventional window, having upright frame members 11 connected by a lintel 60 12 at the top.

The frame, shown in greater detail in Figure 2, includes inner and outer casings 14 and 15 respectively, joined at their inner edges by a stile 16, the space at the rear of 65 which is utilized by sash counterweights 17.

Engaged at the front edge of the casing plate 14 is a guide moulding 18, while at the opposite outer side is a similar element 19, a parting strip 20 occupying a position mid-way therebetween.

The two sashes 21 and 22, respectively inner and outer, are composed of the usual frame work, in which are set panes of glass 23, and it is to be noted for reasons further on apparent, that the outer sash 22 is of slightly 75 lesser width than the inner or front sash 21.

Between the parting strip 20 and mouldings 18 and 19 are open spaces in which the sashes of ordinary windows normally slide. 80

In the present improvement, the sashes are reduced in width to clear the moulding and strips, and metallic plates 25 are fixed directly to the stile 16 within the mentioned spaces 85 ordinarily guiding the sashes.

These plates 25 extend the full length of the window stile from the sill 10 to the lintel 12, and integral with the plates 25 are flanges 26 and 27 respectively at their forward and rear edges, each of these flanges being bent 90 inwardly to produce angular guides 28 and 29, thence continuing as at 30—31, in the plane of the members 26—27, the latter being of greater width than the former.

The flange 30 terminates in an indent right 95 angular guide 32, while the flange 31 is similarly indent forming a guide 33 which extends outwardly to a greater distance than the corresponding front guide 32.

A metal block 34 is provided with angular 100

ly grooved side edges adapted to engage and freely move on the angular guides 28 and 29, the block being recessed, as at 35, on its outer sides to receive a metal plate 36, through 5 which passes a pivot screw 37 also passing through the lower portion of the block 34, and rigidly set in the lower member of the window sash 21 so that the sash pivots on the body of the screw.

10 Between the block 34 and side element of the window sash is a metal plate 38 attached to the sash edge by screws 39 passing through openings 39', the plate extending coincident with the full height of the sash.

15 A portion of the plate 38 is pressed inwardly forming an offset 40 seating within a corresponding recess in the side of the sash frame, this plate being cut away at its upper end, as at 41, to receive a stud 42, clamped by the 20 arms of a double armed spring detent 43, when the sash is in an upright position, the detent being secured by a headed pin 54.

25 Adjacent, but free of the plate 38, at its offset portion 40, is a flat link 44 connected to the plate by a pivotal rivet 45 near its lower end, while in its upper end is set a stud 46 pivotally connecting another block 48.

30 The block 48 is grooved at its side edges to slide on the angle guides 28 and 29, and has undercut, opposed recesses 49 to slidably receive the plate 36, the upper of which presents a transverse friction bar 50, its ends impinging against the plate 25 and entering the 35 spaces immediately within the elements 26 and 27, the stud 42 being rigidly secured in the plate 49. A continuation of the plate 36 has an opening 54 in which is secured the end of a chain running over a pulley and provided with a weight counterbalancing the 40 sash as is usual.

35 Formed in the lower portion of the plate 36 are a series of spaced perforations 51 engageable by a spring detent 52, the shank of which is held by a nut 53 to the stud 46 set in the block 48.

40 From the foregoing it will be seen that when the sashes are turned angularly, the plate 38—40 is moved with the sash, actuating the link 44 and causing the detent 52 to engage one or another of the openings 51 with sufficient tension to hold the window sash in its adjusted position.

45 When the sashes are closed the knob 42 is encircled by the spring 43, an opening being formed in the sash frame to accommodate this knob.

50 From the foregoing it will be apparent that a very simple device has been disclosed, its parts being entirely of metal, light in weight and readily formed by ordinary die processes; the arrangement is such as to positively prevent the entrance of wind or rain to the interior and that all wearing surfaces are of ample size to resist wear indefinitely.

55 60 65 70 75 80 85 90 95 100 105 110 115 120 125 130 While certain preferred embodiments of

this device have been shown and described, it will be understood that changes in the form, arrangements, proportions, sizes and details thereof may be made without departing from the scope of the invention as defined in the appended claims.

Having thus described the invention, what is claimed as new and desired to secure by Letters Patent, is:—

1. A window comprising in combination with a wooden window frame having plain stiles provided with rails, and inner and outer sashes, of metal plates extending over the entire length of said stiles between said rails, inreaching grooved flanges on both edges of said plates, metal strips on the lateral edges of said sashes, blocks, respectively upper and lower, slidably engaged by said flanges, links connecting said blocks, and screws passed pivotally through said lower blocks and strips directly into the lower portions of said sashes.

2. A window comprising in combination with a wooden window frame having plain stiles provided with rails, and inner and outer sashes slidable therein, of metal channels secured on said stiles between pairs of said rails, said channels having opposed inreaching guides in their flanged portions extending throughout the height of the window frame, inner and outer sashes having metal strips on their lateral edges, upper and lower blocks engaged by said guides, bars slidably engaged by the upper blocks, said bars having means at their upper ends to engage counterbalances for said sashes, links connecting said blocks, pivot screws passing through the lower block and bar into the sash near its lower edge, and means to retain the sash in adjusted angular positions.

3. In a window, a metallic guide channel fixed on the frame slide ways, said channel having opposed flanges presenting inreaching angular guides extending the full length of a window frame, a sheet metal strip fixed on the lateral edge of the window sash, a block having grooved edges to engage said angular guides, a pivot passing through said block and strip to directly engage the window sash near its lower edge, a second block slidable in said guides, a link connecting said blocks, a stud carried by said metal strip, and a double armed resilient catch to engage said stud to retain the sash when in an upright position.

4. In a window having a frame and inner and outer sashes hung therein, metallic guide channels fixed on opposite sides of the frame, metal plates on the lateral edges of the sashes, pairs of blocks, respectively upper and lower, slidable in said channels, pivots for the lower blocks set directly in the sashes at their bottom portions, links connecting the upper and lower blocks, inreaching flanges on the edges of said channels to en-

gage the edge portions of said plates, pairs of plates rotatable on said pivots, said plates having a series of spaced apart openings, and spring detents carried by said sash to engage selectively in the plate opening there-
5 by to retain the sash in angular adjustment.

5. In a window, a frame having opposed flat surfaced vertical stiles, inner and outer sash retaining rails, a parting strip intermediate the rails, sheet metal channel shaped guides fixed in the spaces between the rails and parting strip, said guides having in-reaching longitudinal projections extending the full height of the window, inturned flanges on the edges of said channels, the rear flange projecting further inwardly than the front flange, a sheet metal strip attached to the edges of the sashes, said sheet metal strip being slidable under the rear flange and over the front flange and having an inwardly offset portion, upper and lower blocks slidable in said guides, a pivot connecting the lower blocks to the lower portion of the sash, and flat links connecting the upper and lower blocks, said links being partially engageable in the recesses of said strips.

6. In a double hung window, a frame having longitudinal grooves in its inner side surfaces, channels fixed therein having opposed guides in their side members and in-reaching flanges at the edges of the side members respectively front and rear, sashes having plates on their side edges, said plates engaging the inner surfaces of the front flanges, upper and lower blocks slidable in said channels and engaging the guides therein, links pivotally connecting between said upper blocks and plates on the sashes, and pivots passing through the lower blocks into the sash sides whereby the sashes may be angularly inclined.

7. In a double hung window, a frame having longitudinal grooves in its inner side surfaces, channels fixed therein having opposed guides in their side members, sashes having metal plates on their side edges, upper and lower blocks slidably engaged by the guides of said channels, links pivotally connecting the upper blocks to said sash plates, pivots connecting the lower blocks to the sash, and means in said metal plates cooperative with said blocks to limit the swinging action of the sash upon said pivots.

55 8. In a double hung window, a frame having longitudinal grooves in its inner side surfaces, channels fixed therein having opposed guides in their side members, sashes having metal plates on their side edges, upper and lower blocks slidably engaged by the guides of said channels, links pivotally connecting the upper blocks to said sash plates, pivots connecting the lower blocks to the sash, bars held by said pivots in the lower blocks to extend slidably through the upper blocks,

said bars having a series of spaced perforations, and spring detents on the upper blocks to resiliently engage in the bar perforations as the sashes are swung on their pivots.

9. In a double hung window, a frame having longitudinal grooves in its inner side surfaces, channels fixed therein having opposed guides in their side members, sashes having metal plates on their side edges, upper and lower blocks slidably engaged by the guides of said channels, links pivotally connecting the upper blocks to said sash plates, pivots connecting the lower blocks to the sash, bars fixed in the lower blocks to extend slidably through the upper blocks, heads on said bars to engage the channel guides remotely beyond the upper blocks, said bars having a plurality of perforations, and spring detents on the upper blocks to engage in the perforations as the upper blocks are actuated by said links in swinging the sashes.

10. In a double hung window, a frame having longitudinal grooves in its inner side surfaces, channels fixed therein having opposed guides in their side members, sashes having metal plates on their side edges, upper and lower blocks slidably engaged by the guides of said channels, links pivotally connecting the upper blocks to said sash plates, pivots connecting the lower blocks to the sash, bars fixed in the lower blocks to extend slidably through the upper blocks, heads on said bars to engage the channel guides remotely beyond the upper blocks, pins in said heads to enter recesses in the sash plates, means on said plates to resiliently engage said pins when the sashes are upright, spring detents carried by the upper sliding blocks, and means in said bars to engage said detents whereby the sash are held at variant angles.

11. In a double hung window, a frame and sash therein, channelled guides fixed in the sash run ways from top to bottom, flat plates fixed on the side edges of the sash to extend the full length thereof, blocks pivoted to the lower portions of the sash, other blocks linked connected with the first named blocks, all of said blocks being interengaged to slide in said guides, strips pivotally attached to the second named slides, said strips having a plurality of spaced openings, detents engageable in the openings to retain the sash in angular adjustment, and resilient means to secure the sash when in normal upright position.

In testimony whereof we affix our signatures.

ROBERT MONSCH.
